UNITED STATES PATENT OFFICE.

ANDREW D. WARD, OF AUGUSTA, MAINE.

WRENCH.

SPECIFICATION forming part of Letters Patent No. 352,433, dated November 9, 1886.

Application filed May 12, 1886. Serial No. 201,970. (No model.)

To all whom it may concern:

Be it known that I, ANDREW D. WARD, a citizen of the United States, and a resident of Augusta, in the county of Kennebec and State 5 of Maine, have invented certain new and useful Improvements in Wrenches, of which the following is a full, clear, and exact description, which will enable others skilled in the art to which it appertains to make and use the 10 same.

My invention relates to pipe-wrenches in which a movable jaw is used; and it consists of the use, in such a pipe-wrench, of a toothed jaw pivoted at its back end to a slide which 15 is joined to a second slide by means of a screw having a milled thumb-wheel, the last-mentioned slide being held from sliding backward by means of ratchet-teeth, which engage corresponding teeth on the bar of the wrench. 20 This slide also has a spring which holds it down to the toothed bar, and which admits of the slide being lifted away from the teeth and moved freely along the bar for rapid adjustment, leaving the connecting-screw for the 25 more accurate adjustment necessary to the operation of a pipe-wrench.

My invention is fully illustrated in the accompanying drawings, in which Figure 1 shows a central longitudinal section. Fig. 2 is a front 30 elevation; Fig. 3, a sectional detail of Fig. 1.

A is the bar of the wrench, and A' is the fixed jaw at its end. One edge of the bar A is provided with ratchet-teeth a a. A movable tooth-faced jaw, B, having a yoke, B', fitting around the bar A, is pivoted at its back 35 end to the slide D by means of the pivot b. The yoke B' is so constructed as to allow the free or toothed end of the jaw B a limited amount of motion to and from the bar A.

40 Secured to the upper side of the jaw B is the spring C, one end of which rests on the projecting portion d of the slide D, to which the jaw B is pivoted. The force of the spring C tends to raise the free end of the jaw B from the bar A. The end of the jaw B is fitted 45 against a shoulder on the end of the projecting portion d, so that the pivot b is relieved from any pressure. A second slide, E, follows the slide D, to which it is connected by means 50 of a screw, H, one end of which enters a recess, i, in the slide D, and is there confined by the

pin i', playing in the groove i, cut near the end of the screw, while the opposite end passes through the slide E, which is tapped out to receive it.

55 The screw H is turned by means of the milled thumb-wheel I, placed immediately back of the slide D. The slide E is provided with ratchet-teeth e e, which engage the teeth a a, and prevent the slide from moving backward, but allow it to be moved forward.

The slide E is made somewhat larger than the bar A in the direction of its greatest thickness, and between the back edge of the bar and the inside surface of the slide is the spring F, 65 which rests against the edge of the bar and tends to keep the teeth a a and e e interlocked. A thumb-screw, G, is provided, to regulate the tension of the spring F.

70 My wrench is operated as follows, viz: The slide E is pressed upward against the force of the spring F, so that the teeth e e clear the teeth a a. The jaw B is then roughly adjusted by moving the slide E, with the parts attached thereto, rapidly along the bar A. The end of 75 the jaw B is then slightly depressed with the thumb, and its toothed edge adjusted against the pipe by turning the screw H. If, now, the wrench is turned in the direction shown by the arrow, the jaw B will be forced down against 80 the bar A, and at the same time the teeth will be set into the sides of the pipe. The bar A will thus receive the greater part of the strain at right angles. When the wrench is turned 85 backward, the grip of the jaw B is easily relaxed from the pipe, and it will be found to work without binding while clinging closely to the pipe. When properly set, it may easily be worked with one hand. A spiral or other spring may be inserted between the jaw B and 90 the bar A, in place of the spring C.

I claim as my invention and desire to secure by Letters Patent—

1. In a pipe-wrench, the combination ratchet-bar A, having fixed jaw A' at one end, with 95 movable jaw B, having yoke B' fitting around the bar A, the ratchet-slide D, to which the jaw B is pivoted, the block E, and spring F, the screw H, confined to the slide D by pin i', and the thumb-wheel I on the screw H, substantially as shown and described.

2. In a pipe-wrench, the toothed bar A, hav-

ing fixed jaw A', combined with the movable jaw B, having a yoke, B', and a lifting-spring, C, and being pivoted to the slide D, which slide is connected with a second slide, E, by the 5 screw H, having milled thumb-wheel I, said slide being provided with spring F, all substantially as described.

3. In a pipe-wrench, the ratchet-bar A, hav-

ing on its end the fixed jaw A', the pivoted jaw B, having yoke B', the slide D, the screw H, 10 and piece E, the spring F, and thumb-screw G, substantially as described.

ANDREW D. WARD.
